cadia, Calif., assignors to Square D Company, Park
Ridge, Ill., a corporation of Michigan

Filed Feb. 8, 1967, Ser. No. 5,734

Term of patent 14 years

(Cl. D26—13)

FIG. 1 is a perspective view of a raintight fitting for an outdoor enclosure of an electrical device, showing one form of our new design wherein the hub portion of the fitting is relatively small;

FIG. 2 is a top plan view of the fitting shown in FIG. 1;

FIG. 3 is a front elevational view of the fitting shown in FIG. 1, a rear elevational view being a mirror image thereof;

FIG. 4 is a right side elevational view of the fitting shown in FIG. 1, a left side elevational view being a mirror image thereof;

FIG. 5 is a bottom plan view of the fitting shown in FIG. 1;

FIG. 6 is a perspective view of a raintight fitting for an outdoor enclosure of an electrical device, showing another form of our new design wherein the hub portion of the fitting is relatively large;

FIG. 7 is a top plan view of the fitting shown in FIG. 6;

FIG. 8 is a front elevational view of the fitting shown in FIG. 6, a rear elevational view being a mirror image thereof;

FIG. 9 is a right side elevational view of the fitting shown in FIG. 6, a left side elevational view being a mirror image thereof; and

We claim:

The ornamental design for a raintight fitting for an outdoor enclosure of an electrical device, substantially as shown and described.
